MOBILE MARINE DRILLING FOUNDATION
George A. McCammon, Caracas, Venezuela, assignor to
Jersey Production Research Company, a corporation
of Delaware

Filed Aug. 25, 1959, Ser. No. 835,945
2 Claims. (Cl. 61—46.5)

The present invention relates to an improved movable marine foundation. The invention is concerned with an apparatus for drilling oil wells in marine locations and submerged lands which will provide a firm, stable base for the drilling operations and which can be readily transported by floating from one marine location to another. The invention is especially concerned with an apparatus and method for drilling oil wells in marine locations and submerged lands wherein the drilling rig including the substructure, the derrick, the draw-works and auxiliary equipment may be readily transported from one marine location to another marine location.

It is well known in the art to position drilling rigs on barges as an integral part of the barge and to utilize the barge as a drilling base during the drilling of the borehole into the earth's substrata in marine locations. However, this method is relatively expensive, time consuming and very cumbersome to operate. Another method known in the art is to erect permanent foundations above the water and to position thereon the complete drilling rig which can be disassembled after the borehole has been completed. Upon completion of the borehole, this particular type of rig is disassembled, placed upon suitable marine transportation and transported to a new location. The rig is then assembled in the new location. This method is very time consuming and also expensive.

In the art of drilling boreholes into the earth's substrata, many marine drilling operations are carried out at depths from about 20 to 100, to 500 and greater feet below the surface of the water. Wells in these marine locations are dug or drilled to a depth of from 5,000 to 10,000 feet and greater. In order to accomplish this, it is customary to fabricate and position a suitable marine foundation upon which the rig can be erected for the handling of the drilling pipe necessary for drilling the borehole and for conducting the various well completion operations.

These permanent foundations upon which the rig is placed are constructed by various methods. One method, for example, is to drive concrete piling into the substrata of the lake or ocean bottom and thereafter to form a platform 20 to 40 feet above the surface of the water. As pointed out above, the derrick and other rig equipment are then positioned on the platform for the drilling of the borehole and for the completion of the well. These rigs vary greatly in weight as, for example, from about 150 to 200 tons. Also wells may be drilled and completed at various rates as, for example, one about every 20 to 40 days etc. Thus, after well completion, there exists at the present time only two alternates, namely, to leave the rig intact on the foundation and to be dismantled at a later date, or to go through the expensive procedure of disassembling the rig, transporting it to a new location and then reassembling the rig. If this latter procedure be followed on numerous occasions, it is necessary to rework or clean out an existing well. Thus, it is necessary to reassemble the rig for the reworking of the original well and after completion of the reworking to again disassemble the rig including the derrick.

In accordance with the present invention, a movable improved very stable platform is utilized for such drilling operations, thereby effecting great time and many savings. The platform of the present invention may be em-

2

ployed in varying water depths and can be moved from location to location with reasonable facility and minimum cost. This platform provides a sufficiently large and stable area for drilling operations in varying depths of water.

The mobile marine drilling foundation of the present invention comprises a unique system of submergeable pontoons to provide the required bearing on the bottom, a multiple legged columnar structure extending from the pontoons to above water level, and a working platform carrying the derrick and related drilling machinery. Auxiliary machinery, such as mud tanks and pumps, tubular goods storage, etc., may be accommodated by a floating drilling tender or barge which will be anchored at one side of or near the working platform.

The pontoons are arranged so that they will bridge any heterogeneous bottom condition and result in stable foundation. The support of this foundation results from bearing on the bottom or from a combination of buoyancy and bearing due to the displacement by the pontoons of soft bottom soils; the relative amounts of each depend on the type of soil encountered and the buoyant force of the pontoons which can be adjusted through air chambers. Extending upwardly from the pontoons are columnar structures or legs which are rigidly braced to the pontoon system as required by the water depths in which the foundation is used.

The deck substructure or working platform is supported on these upwardly extending legs at the varying heights required by the water depths. The derrick and drilling floor in the preferred structure is cantilevered far enough from the deck structure so that drilling can be done over the side of the foundation. This permits the foundation to be used in conjunction with a small permanent well head protection platform and will allow workovers, such as the return of the foundation to the same location for reworking the well. It further permits, due to its open side approach, the laying of gathering lines and power cables to the well without danger of the pontoon system crushing or damaging such installations.

The pontoon system, legs or columns, bracing, and platform may be fabricated from any suitable materials such as concrete, steel, aluminum, and the like, or may be manufactured of any combinations of these materials, which may be best combined to achieve the desired weights, structural strength, sizes, and resistance to corrosive elements.

The mobile marine drilling foundation, comprising the pontoon system, columns, and working platform complete with derrick and machinery, will be moved as a single unit from one location to the next. A crane barge (floating lifting device), after picking up the foundation and clamping it to the barge, may be towed by a tug to the next location to be drilled. The pontoons preferably will remain submerged during this tow. Water may be removed from the pontoons by pumps or other suitable equipment to adjust the buoyancy and resultant weight to be lifted to reasonable limits.

A clamp is used to make the working platform fast to the columns at the varying heights required. This device consists of a mechanically operated clamp, pins, dogs, etc., which will safely transfer the loads from the working platform to the columns. In addition to this clamping device, an adjusting mechanism is used to level up the derrick and provide for any inclination of the foundation.

The present invention may be readily understood by reference to the drawings illustrating embodiments of the same. FIG. 1 shows the mobile apparatus of the present invention positioned in a marine formation with the derrick above the surface of the water. FIGS. 2, 3 and 4 illustrate structure details of the invention. FIGS.

5, 6 and 7 illustrate in some detail the mobile marine drilling foundation lifting barge. FIG. 8 illustrates the lifting barge in combination with the mobile foundation and method of moving. FIG. 9 illustrates the method of moving the mobile foundation by means of the lifting barge, while FIG. 10 illustrates the method of positioning the mobile foundation by means of the drilling barge on other barges for major overhaul.

Referring specifically to FIG. 1, the equipment is shown positioned beneath the surface of the water 1 on the bottom of the lake or ground beneath the surface of the water. The apparatus comprises three inter-related pontoons 2, 3 and 4 interconnected to one another in a horizontal plane. Pontoons 2 and 4 are arranged with respect to each other as a V with pontoon 3 intercepting these pontoons at approximately their mid-point. Since it is preferred that pontoons 2, 3 and 4 be substantially equal in length and diameter, pontoon 3 will over-extend pontoons 2 and 4, thereby greatly increasing the stability of the foundation. In effect, these three pontoons form an A frame with a cross connecting member over-extending the other two members in order to secure added stability.

Two vertically extending legs 6 and 7 extend upwardly from the cross connecting pontoon 3 and are positioned on pontoon 3 between the points where the V connected pontoons 2 and 4 intersect pontoon 3. A third vertically extending leg 8 is supported by braces 13 and 14, which braces extend angularly from pontoons 4 and 2, respectively.

A lower platform 15 is supported above the surface of the water by means of the vertically extending legs 6, 7 and 8. Brace 9 angularly extending inwardly from pontoon 3 supports leg 6, whereas brace 10 angularly extending inwardly from pontoon 3 supports leg 7. Brace 11 extending from pontoon 2, and brace 12 extending from pontoon 4, further support leg 8. Horizontal braces 18, 19 and 20 support upwardly extending legs 6, 7 and 8 with respect to one another. The derrick floor 16 is positioned above deck substructure 15 and supports derrick 17. The drilling floor 16 over-extends substructure 15 and thus permits the drilling operation to be carried out in an off-center position, preferably, in the area delineated by the cross member pontoon and the base of the V members generally designated as lake or sea bottom 5. The upwardly extending legs are positioned preferably in equal distance one from the other.

It is to be understood that the drilling equipment such as drill pipe, handling equipment, motivating equipment, the method and means of changing the buoyancy of the pontoons, the method of equalizing the buoyancy of the respective pontoons are not shown since these features are not part of the present invention. Furthermore, these features are well known in the marine drilling art.

However, it is to be understood that the buoyancy of one pontoon may be varied and different from the buoyancy of each of the other two. Thus, by varying the buoyancy of one pontoon with respect to the others, depending upon the nature of the subsoil, greater stability is secured. It is within the concept of the present invention to provide air chambers in each of the respective pontoons so as to have a different buoyancy as required at one end of the pontoon as compared with the other end of the pontoon, or one section of the individual pontoon as compared to the buoyancy of another section. Thus, by way of example, areas A, B, C, D, E, F and G of the respective pontoons may each have a different buoyancy, depending upon the nature of the subsoil. As pointed out heretofore, the method and means for ejecting or admitting water and air to the respective areas is not illustrated since this does not constitute a part of the present invention. Any satisfactory means, such as air lines, check valves, pumping means, and the like, may be employed. FIG. 2 is a plane view taken through A—A. FIG. 3 is a front view looking toward the over-

extending platform section, while FIG. 4 is a side view. Similar parts described in FIG. 1 are illustrated with similar numbers in FIGS. 2, 3 and 4. The well position with respect to the substructure is designated by 21 in FIG. 2.

While the precise measurements used for the various members will vary, depending upon the nature of the drilling operation to be carried out as, for example, the depth of the water, the size and weight of the derrick and auxiliary equipment and the diameter of the borehole to be drilled as well as the depth and other drilling factors, one satisfactory unit is one wherein the lengths of the pontoons are approximately 210 feet. The lengths may vary from about 100 feet to about 400 feet and longer. Under these conditions, pontoons 2 and 4 are V positioned so that the height of the V is approximately 182 feet. Pontoon 3 would intercept pontoons 2 and 4 approximately 73 feet from the top of the V and about 109 feet from the bottom of the V. The overall height of the legs would approximate about 110 feet below the water and about 30 feet above the water, thus permitting the drilling platform to be positioned above the surface of the water from about 0 feet to 30 feet. The diameter of the pontoons may vary appreciably, but are generally in the range from about 10 to 20 feet. With respect to the particular apparatus illustrated, the diameter of the pontoons is approximately 12 feet.

Reference is made to FIGS. 5, 6 and 7, showing the general arrangement of the floating lifting device arrangement for removing the substructure and equipment from the mobile marine drilling foundation by means of the floating lifting device. FIG. 5 shows a top view of the floating lifting device, FIG. 6 shows a side view, while FIG. 7 illustrates an end view. Similar parts in the respective figures are designated by similar numbers.

Referring specifically to the figures, the floating lifting device on barge 40 contains at one end thereof outwardly extending booms 41 and 51. A hoist 42 is shown positioned on boom 51. The booms are supported by a mast 44 which is in turn supported by a mast brace 45. The boom is supported by boom rig 43 extending from mast 44. Hoist rigging 43 extending to winch 48 and 49 is illustrated in the respective views. Power equipment to run the hoist and the barge is illustrated by 47.

Reference is made to FIG. 8 showing the general arrangement for removing the substructure and equipment from the mobile marine drilling foundation by means of the floating lifting device. The upper and lower platform 15 and 16 by means of suitable equipment can be released from legs 6, 7 and 8 or locked on to these legs and the substructure of the equipment. Thus, in operation, the drilling platform comprising the derrick, the platform floors and the pontoon structure, can be moved as a single unit, or the derrick and platforms can be moved separately from the pontoon structure. The method of raising the platform floors 15 and 16, or lowering said floors with respect to the legs 6, 7 and 8 is not shown. Suitable means well known in the art may be employed. In general, utilizing the two hoists 42 and 62 attached to booms 51 and 41, respectively, permits these hoists to be attached to separate sides of the equipment, thereby gaining much greater stability. Similar parts of FIG. 8 with respect to the previously described figures are designated by similar numbers.

FIG. 9 illustrates a position of the mobile marine drilling foundation and the floating lifting device during transportation. It is to be noted that in this method of operation the respective platforms supporting the derrick are located and locked on legs 6, 7 and 8, thus permitting the transportation of the entire apparatus as an integral unit. Similar parts of FIG. 9 illustrated in the preceding drawings are similarly numbered.

Reference is made to FIG. 10 which illustrates the arrangement of the mobile marine drilling foundation removed from the water by means of the floating lifting

device and readily placed upon floating barges for the purposes of major maintenance and overhaul. Similar elements of FIG. 10 previously described in preceding drawings are similarly numbered. By way of example, in operation the procedural steps for moving the present foundation unit from a shallow water location to a deep water location comprises:

Using the lifting crane, the deck is raised to a height required for the deep water location. The deck is made fast to points atop the columns for the lifting and towing unit. Water is removed from the pontoons. The unit is lifted clear of the lake bottom and clamped to the crane barge and towed to a deep water location. The unit is freed from the barge and lowered to rest on the bottom by flooding the pontoons. The deck structure is leveled on the columns as required by the sloping lake bottom.

Water is displaced partially from the pontoons to increase buoyancy. Positive buoyancy should never be achieved. The foundation unit is then ready for operation.

If the foundation unit is to be moved from a deep water location to a shallow water location, the following procedural steps are employed: The hoists are made fast to lifting points atop the columns and water is removed from the pontoons. The unit is lifted clear of the lake bottom and the column structure is clamped to the crane barge. The unit is towed to a shallow water location. The foundation unit is freed of the barge and lowered to rest on the bottom and the pontoons are flooded. Using the lifting crane, the deck is lowered as required for the shallow water location. The deck structure is leveled on the columns as required by the sloping lake bottom. The water is displaced from the pontoons to increase the buoyancy but positive buoyancy should never be achieved. The foundation unit is now ready for operation.

The apparatus of the present invention has the following advantages:

It is a self-contained foundation unit for drilling which is readily and efficiently transported by a floating lifting device from one location to the next.

It comprises a self-contained foundation unit for drilling which is lifted by a floating lifting device and may be towed with its pontoon structure submerged from one location to the next. The unit comprises a self-contained foundation unit for drilling which is lifted by a floating lifting device (crane barge) and is clamped to the stern of the lifting barge and is towed with its pontoon structure submerged from one location to the next. The unit also comprises a self-contained foundation unit for drilling which is lifted by a floating lifting device (crane barge) and is clamped to the stern of the lifting barge, and is towed with its pontoon structure submerged, thereby eliminating the use of special devices such as outriggers, auxiliary buoyancy units, and similar methods of obtaining floating stability. Also the stability of the foundation unit during the lifting and moving is due to the principles involved in the carrying mechanism, and therefore does not have to be incorporated into the design of the foundation unit proper.

The foundation is stable under all soil conditions due to the use of the bearing area provided by the pontoons plus the buoyancy achieved through the volume of the pontoons and the arrangement for varying buoyancy through the air chambers. The use of the bearing area provided by the pontoons, plus the buoyancy achieved through the volume of the pontoons and the arrangement for varying the buoyancy through the respective air chambers allows the foundation to be very stable under all soil conditions and allows a preloaded condition to be established to a minimum, which reduces the movement due to working.

The use of the bearing area provided by the pontoons plus the buoyancy achieved through the volume of the pontoons and the arrangement for varying the buoyancy through air chambers allows the foundation to be stable

under all soil conditions and allows a preloaded condition to be established. It also permits the weight of the mobile foundation to be adjusted for optimum carrying conditions. Also the arrangements for varying the buoyancy through air chambers allows a maximum unit weight to be established during the drilling operations while the foundation unit is on the bottom, and at the same time allows a minimum unit weight to be established during lifting and towing operations. This principle of separate weights for the various operations makes possible the use of a lesser capacity and, therefore, a more efficient carrying device.

The arrangement of the cantilevered deck and the open pontoons system allows this foundation to be used not only for original drilling, but also to be moved back in on the same location for subsequent workovers and routine maintenance. Also the arrangement of the cantilevered deck and the open pontoon system allows this foundation to be used in connection with a permanent production platform and at the same time permits flow lines, power cables and similar utilities to be run to the well site without suffering any damage in connection with repeated relocations of the foundation.

The triangular arrangement of the three pontoons, in the form of an A, results in an extremely stable foundation. The use of the lifting device to lift and vary the height of the working platform in accordance with water depths, without the use of jacks, screws, mechanical ratchets or similar devices which would have to be integral parts of the foundation or be applied from an outside force, is very efficient.

What is claimed is:

1. An improved foundation for conducting drilling operations in a marine location which comprises a substantially horizontal base structure of interconnected pontoons, a vertically extending network of columns and braces secured to said pontoon base, and a substantially horizontal working platform supported by said network; said base comprising first and second elongated, submergible pontoons joined at a substantial angle, and a third pontoon cross-connecting said first and second pontoons to form a substantially A-shaped configuration, with said third pontoon extending beyond each of its respective intersections with said first and second pontoons to secure added stability; said vertically extending network comprising first and second vertically disposed columnar members secured to said third pontoon between said first and second pontoons, and a third vertically disposed columnar member extending above the triangular area enclosed by said pontoons and supported by braces interconnecting said first and second pontoons therewith; said working platform comprising a cantilevered derrick floor extending horizontally above the area which lies between said first and second pontoons, but outside said enclosed triangular area.

2. An improved foundation for conducting drilling operations in a marine location which comprises a working platform adapted to have positioned thereon a derrick and auxiliary equipment, a base of three interconnected pontoons arranged in a horizontal plane to form an A-shaped structure with a cross-pontoon over-extending each of two other pontoons, means to vary the buoyancy of said pontoons individually, and a vertically extending structure securely attached to said pontoons, to which is attached said working platform; said vertically extending structure comprising three vertically extending legs which support said working platform, two of said vertically extending legs being attached to said cross-pontoon between the two intersections of said cross-pontoon with the other two pontoons, the third leg being disposed vertically above the triangular area enclosed by the intersecting three pontoons, said third leg being supported by brace members extending angularly therefrom and attached to said two other pontoons; said working platform comprising a cantilevered derrick floor extending horizontally above the

area partially enclosed by said cross-pontoon and the diverging end portions of said two other pontoons, whereby the center of said derrick floor lies vertically above said partially enclosed area.
